UNITED STATES PATENT OFFICE.

HERBERT G. OLIVER, OF NEW YORK, N. Y.

REEL FOR PHOTOGRAPHIC FILMS.

1,420,056.

Specification of Letters Patent. Patented June 20, 1922.

Application filed September 1, 1920. Serial No. 407,356.

To all whom it may concern:

Be it known that I, HERBERT G. OLIVER, a citizen of the United States, and a resident of the city of New York, borough of Manhattan, in the county and State of New York, have invented certain new and useful Improvements in Reels for Photographic Films, of which the following is a full, clear, and exact description.

10 Among the principal objects which the present invention has in view are: To strengthen the construction; to simplify the repair thereof in the event of damage thereto; to ventilate the film when held within 15 the reel; to simplify the method of holding the end of a ribbon or film in the reel for re-winding; and to simplify and cheapen the construction.

Drawings.

20 Figure 1 is a side elevation of a reel constructed in accordance with the present invention;

Figure 2 is a section thereof, the section 25 being taken on the line 2—2 in Figure 1;

Figure 3 is a section on enlarged scale, the section being taken as on the line 3—3 in Figure 2.

Description.

30 Heretofore the rolls of photographic film have been carried on reels or spools preferably constructed from sheet metal, mounted upon a central core. The reels have been 35 necessarily light, and subject to injury such as that of being crushed out of shape when lying on the floor after being emptied of the film. The metal from which these reels are constructed is made light to save the weight 40 thereof, which becomes a serious factor in the transportation or transshipment of the films.

To avoid the difficulty referred to, I have constructed reels from stout wire, employing 45 continuous rings 9, which are rigidly connected to the terminals of the extensions of U-shaped members 10. The members 10 are radially disposed with reference to the rings 9, and the cross members 11 of the 50 members 10 are held in spaced relation by cheek pieces, or discs 12. The edges of the discs 12 are recessed to receive the cross pieces 11, as shown best in Figure 1 of the drawings.

To strengthen the construction small wire 55 rings 13 are rigidly attached to the cross members 11 either by welding or soldering the ring and members where the same engage, or by any other suitable and practicable means. The rings 13 also act as stop 60 members for regulating the position of the discs 12, which, as shown in Figure 2 of the drawings, are pressed closely on the said rings. The discs 12 are held in service position by the tube 14. The tube 14, as shown 65 best in Figure 3 of the drawings, has an offset keyway 15, pressed therein to align with the key formed on the winding mandrel for reels of this character.

The extremities of the tube 14 are over- 70 turned to form the rivet heads 16. When the heads 16 are overturned on the said discs 12, the said discs are held rigidly in position.

To form the body of the spool or drum on 75 which the reel is wound, I employ a section of spring metal 17. One end of the section 17 is bent to form a hook 18, the extremity whereof forms, with the body of the section 17, a throat, contracted to a dimension 80 slightly less than the thickness of the member 11. This serves to hold the section 17 in its relation to the reel at all times.

The opposite end of the section 17 is shaped to form the clasp end 19, which conforms 85 with the hook 18, to co-operate therewith for holding the inner end of the film when the same is being wound thereon.

As shown by dotted lines in Figure 3 of the drawings, the clasp 19 may be pressed 90 out of engagement with the hook 18 by pressure applied on the section 17 which, when released, resumes its service position, shown by the full lines in said figure, engaging in holding relation the end of the 95 film between the said end 19 and hook 18.

The skeleton form in which the reel is constructed allows for the use of material having great strength, without exceeding the established limit of weight in the completed 100 reel. If perchance the reel should be crushed the difficulty in making the repair is materially lessened, due to the reason that all that in all probability would be injured would be the members 10. The members 10 would be bent together. This would merely require the exercise of sufficient 105 strength to pull them apart to their original

shape or dimensions. It will be noted that the central structure forming the drum on which the reel would be wound is practically indestructible.

5 *Claims.*

1. A reel as characterized having marginal rings disposed in spaced relation; a plurality of U-shaped supports therefor, said supports being disposed in spaced relation and radially to said rings, said supports having cross members removed from the center of said rings; and a drum for winding a film, said drum engaging said cross members for holding the same in spaced relation.
- 10 2. A reel as characterized having marginal rings disposed in spaced relation; a plurality of U-shaped supports therefor, said supports being disposed in spaced relation and radially to said rings, said supports having cross members removed from the center of said rings; and a drum for winding a film, said drum engaging said cross members for holding the same in spaced relation, said drum having sheet metal discs recessed at intervals in the periphery thereof for receiving said cross members.
- 15 3. A reel as characterized having marginal rings disposed in spaced relation; a plurality of U-shaped supports therefor, said supports being disposed in spaced relation and radially to said rings, said supports having cross members removed from the center of said rings; a drum for winding a film, said drum engaging said cross members for holding the same in spaced relation, said drum having sheet metal discs recessed at intervals in the periphery thereof for receiving said cross members; and a tube extending through said drum and attached to said discs for holding said discs in service position.
- 20 4. A reel as characterized having mar-

ginal rings disposed in spaced relation; a plurality of U-shaped supports therefor, said supports being disposed in spaced relation and radially to said rings, said supports having cross members removed from the center of said rings; a drum for winding a film, said drum engaging said cross members for holding the same in spaced relation, said drum having sheet metal discs recessed at intervals in the periphery thereof for receiving said cross members; and a tube extending through said drum and attached to said discs for holding said discs in service position, said tube being shaped to form a keyway therein.

5. A reel as characterized having marginal rings disposed in spaced relation; a plurality of U-shaped supports therefor, said supports being disposed in spaced relation and radially to said rings, said supports having cross members removed from the center of said rings; and a drum for winding a film, said drum engaging said cross members for holding the same in spaced relation, said drum embodying a spring metal section the ends whereof are bent to form a pressure opening clasp for holding the end of a film.

6. A reel as characterized having marginal rings disposed in spaced relation; a plurality of U-shaped supports therefor, said supports being disposed in spaced relation and radially to said rings, said supports having cross members removed from the center of said rings; and a drum for winding a film, said drum engaging said cross members for holding the same in spaced relation, said drum embodying a plurality of inwardly disposed wire rings, and a metal section covering therefor, said metal section extending externally to the cross members of said U-shaped supports.

HERBERT G. OLIVER.
